I.D. Mathews,

Shaft Hanger,

№64,344.

Patented Apr. 30, 1867.

Ivan D. Mathews.

United States Patent Office.

ISAAC D. MATHEWS, OF WORCESTER, MASSACHUSETTS.

Letters Patent No. 64,344, dated April 30, 1867.

IMPROVEMENT IN HANGER AND JOURNAL-BOXES FOR SHAFTING.

The Schedule referred to in these Letters Patent and making part of the same.

KNOWN ALL MEN BY THESE PRESENTS:

That I, ISAAC D. MATHEWS, of the city and county of Worcester, and Commonwealth of Massachusetts, have made certain new and useful Improvements in Combined Hangers and Journal-Boxes or Bearings for Shafting; and I do hereby declare that the following is a full, clear, and exact description of the same, reference being had to the accompanying drawings, forming a part of this specification, in which—

Figure 1 represents a perspective view of my improved combined hanger and journal-box.

Figure 2 represents a perspective view of the journal-box or bearing C; and

Figure 3 represents a longitudinal central section of the combined hanger and journal-box, as shown in fig. 1.

In the drawings the part marked A represents the body or main part of the hanger. B the top, which has two slots or openings, *aa*, through which bolts pass to fasten the hanger to the ceiling-beam or plate of the building. From one side of the part A projects a piece, *b*, through which passes a screw, *c*, the point of the latter entering the concavity in the cap *d*, which has a projection, *e*, on its under side to fit in the slot *f*, in one-half of the journal-box or bearing C. A slot, *g*, is made in the part A through which passes a bolt, *D*, by which the part E, upon which the journal-box C rests, is secured to part A. From the under or lower part of A projects the part F, through which passes the sustaining screw G, the latter having a nut, *h*, on its lower end to support the oil or drip-cup H. The journal-box supporting piece E is made in circular form upon the upper side to receive the circular part *m* of the journal-box C. It has also a small projection, *n*, which enters the slot *f*, in the box C, as fully shown in fig. 3. O O are holes, through which oil or other lubricating substance is applied to the bearing or journal of shaft I. It will be noticed that the ends of the journal-box C can move or swing in all directions, thus enabling the shaft to run easily and without binding in the box or springing the hangers. Then again the provision for adjusting the position of the box is very complete. By means of the slots *aa* the entire hanger and box can be adjusted in the usual manner, while the box C can be adjusted up or down without disturbing the main part A; to effect which the screw-bolt *D* is loosened and the screw-spindle *G*, which has a flat head, *p*, to receive a wrench, is turned up or down to lower or elevate the bearing part E, to bring the box C to the desired position, when bolt *D* is tightened up again. By the use of a nut, *h*, the adjusting screw-spindle is made to answer a twofold purpose, viz., that of adjusting the bearing part E, and also as a support to the oil or drip-pan H. Both parts of the box C are made alike so that in case the lower half becomes worn, or for any other purpose it becomes desirable, the box C can be used the other side *up*. When in use the points *n* and *e* keep the box C from becoming displaced, while at the same time allowing the box to twist in its socket formed in the piece E sufficiently to permit the box C to conform freely to the position of the shafting as it revolves as above stated. By the use of the screw *c*, in the projection *b*, in combination with the cap piece *d*, the box is retained in position, and that, too, without preventing the free motions of the box as above described.

Having described my improved combined hanger and journal-box, what I claim therein as new and of my invention, and desire to secure by Letters Patent, is—

1. The combination of the main part A, having a slot, *g*, projections *b* F, screw-bolts *D*, *G*, and *c*, with the bearing-piece E, and box C, said parts being constructed and arranged for joint operation, substantially as and for the purposes set forth.
2. The combination of screw *c* and cap *d* with the journal-box C, and projection *b*, of the hanger part A, substantially as and for the purposes set forth.
3. The combination, with the concaved bearing part E, and cap *d*, having projections *n* and *e* as shown, of the journal-box C, having slots or recesses *ff* for the purposes set forth.
4. The combination of nut *h* and screw *G* with the projection F, and oil or drip-pan H, substantially as set forth.

ISAAC D. MATHEWS.
